Primary Examiner — Jack Reickel*Assistant Examiner* — Michael A Kervin(74) *Attorney, Agent, or Firm* — Fox Rothschild LLP(57) **CLAIM**

The ornamental design for a plant waterer soil spike as shown and described.

DESCRIPTION

FIG. 1 is a front, bottom, right perspective-view of a plant waterer soil spike according to the present disclosure;

FIG. 2 is a front view thereof;

FIG. 3 is a rear view thereof;

FIG. 4 is a left-side view thereof;

FIG. 5 is a right-side view thereof; and,

FIG. 6 is a bottom view thereof.

The broken lines in the figures illustrate portions of the article that form no part of the claimed design.

1 Claim, 6 Drawing Sheets(56)
